GASEOUS ELECTRIC DISCHARGE DEVICE

Johannes Gijsbertus Wilhelm Mulder, Eindhoven,
Netherlands, assignor to General Electric Com-
pany, a corporation of New York

Application November 9, 1932, Serial No. 641,910
In the Netherlands November 12, 1931

2 Claims. (Cl. 176—124)

The present invention relates to gaseous electric discharge devices generally and more particularly the invention relates to such devices in which the electric discharge is of the positive 8 column type.

Such devices have a negative characteristic, that is, they require an increase of voltage as the current value is decreased and for this reason a series connected resistance or other ballasting device is provided to regulate the electric discharge device. A considerable part of the total energy 10 used by the device is consumed in this series resistance.

The object of the present invention is to provide 15 a method and a means for operating gaseous electric discharge devices whereby the ballasting device now used in the art is eliminated. A further object of the invention is to provide a regulatory means for gaseous electric discharge devices which is more efficient than those now 20 known in the art. Still further objects and advantages attaching to the device and to its operation will be apparent to those skilled in the art from the following particular description and 25 from the appended claims.

In accordance with these objects the invention 30 comprises a circuit whereby the current supplied to a gaseous electric discharge lamp device periodically falls to zero and another gaseous electric discharge regulatory device provided with a 35 grid is connected in series with said lamp device. I have discovered that regulation of the lamp device is effected where the potential supplied to the grid of said regulatory device is in such relation to the potential supplied to the electrodes of the lamp device that said grid potential is always negative when said electrode potential becomes positive and does not become positive until some 40 time thereafter.

Take, for example, an electric discharge lamp 45 device connected to a direct current source and a circuit for said lamp device whereby the current on the electrodes of said lamp device is periodically reduced to zero by a circuit interrupter. If, at the instant that said electrode current is at zero, a negative potential is impressed on the grid of the regulatory device connected in series with 50 said lamp device, the current flow between said electrodes will not take place even when the electrode circuit is again made. Current flow between the electrodes will again take place only when the grid potential reaches zero or becomes positive. The duration of current flow between the electrodes of the lamp device and therewith 55 the mean current value thereof is controlled by

increasing, or decreasing the interval between the instant that the electrode current is at zero and the instant that the grid potential reaches zero or becomes positive. The discharge current of said lamp device is thus regulated with no 60 appreciable loss of energy.

When the electric discharge lamp device is operating on direct current, as above, only a negative potential is applied to the grid of the regulatory device, where desired, and a switch 65 is provided in the grid circuit to control the grid potential in such manner that the negative potential is applied to said grid only when the current on the electrodes is at zero and is disconnected from said grid at a predetermined interval after 70 current is again applied to the electrodes to accomplish the desired result set forth above.

In the preferred embodiment of my invention the gaseous electric discharge lamp device is connected to a source of alternating current and an 75 alternating current is applied to the grid of the regulatory device, the phase of the grid potential of the regulatory device lagging behind that of the potential applied to the electrodes of the lamp device. This phase lag is accomplished by simple, adjustable means by which the magnitude of current flow through the lamp device is regulated and the phase lag is changed, when desired, by a small rotating condenser or a small variable 80 resistance. By changing the phase lag of the grid potential the magnitude of current flow through the lamp device is changed and thus the intensity of the light emitted by said lamp device is controlled in a simple manner.

Where the lamp device is connected to an alternating current source it is advantageous that said device have two anodes and to connect a regulatory device having a thermionic cathode, a grid, and an anode in the leads of each of said anodes. Current then flows through the lamp device during each half-cycle of the alternating current.

In the drawing accompanying and forming part of this specification several embodiments of my invention are shown, in which

Fig. 1 is a schematic view of one embodiment of my invention,

Fig. 2 is a graph showing the relation of the potential of the electrode circuit of the lamp device to the potential of the grid circuit of the 105 regulatory device,

Fig. 3 is a schematic view of another embodiment of my invention, and

Fig. 4 is a schematic view of another embodiment of my invention.

Like numbers denote like parts in all the figures.

Referring to Fig. 1 of the drawing the gaseous electric discharge lamp device comprises an elongated container 1 having electrodes 2 and 3 sealed therein. Said electrodes are cold sheet-metal electrodes and are made of iron, for example. Said container 1 is filled with a gaseous atmosphere, such as neon, at a few millimeters pressure. Said lamp device has a negative volt-ampere characteristic and is of the positive column type. A regulatory gaseous electric discharge device comprising a container 4 filled with a gas, such as argon, at a few millimeters pressure and having a thermionic cathode 5, an anode 6 and a grid 7 is connected in series with said lamp device.

The cathode 5 of the regulatory device and the electrode 3 of the lamp device are connected to the secondary 12 of a transformer 11 and the primary 10 of said transformer 11 is connected and disconnected from the terminals 8 of an alternating current source by switch 9. The cathode 5 and the grid 7 of the regulatory device are connected to the secondary 18 of the transformer 17, resistance 19 being connected into the current lead connecting grid 7 with secondary 18. The primary 16 of said transformer 17 is connected into a circuit including an inductance 15 and a variable resistance 14, said inductance 15 and said resistance 14 being connected in parallel and the circuit being connected to the terminals 8.

The above described apparatus is started into operation by connecting the cathode 5 to a suitable source of current which heats said cathode 5 to its operating temperature. After said cathode has attained its operating temperature switch 9 is closed and the regulatory device and the lamp device are started into operation. Said inductance 15 and said resistance 14 are in such relation to each other that the potential phase of the secondary 18 lags with respect to the potential phase of secondary 12 during the operation of the device.

The relation between the two potential phases is indicated in the graph shown in Fig. 2 wherein curve 20 represents the rise and fall of the potential of secondary 12 and curve 21 represents the rise and fall of potential of secondary 18, that is, the potential phase changes of grid 7 with respect to said cathode 5. At the instant that the potential represented by curve 20 is at zero there is, of course, no current flow through the series connected discharge devices. Even though this potential becomes positive and increases to the point that the flow of current would normally occur through said device no current flow takes place if the potential represented by curve 21 is negative and this continues until this potential becomes zero or positive. As soon as the potential represented by curve 21 becomes zero, or positive, the current starts to flow in said series connected discharge devices and continues until the potential represented by curve 20 again becomes zero. Current flow through said series connected discharge devices is represented by curve 22. The mean value of the current represented by line 22 is determined by the potential phase difference between the potential represented by curve 20 and that represented by curve 21 and this phase difference and therewith the mean value of the current is increased, or decreased, as desired by adjusting variable resistance 14.

From the foregoing it will be understood, of course, that current flows through said series con-

nected discharge device only during the positive phase of the alternating cycle and only during part of that phase, which gives an intermittent effect to the light emitted by the lamp device. If this is not desired the frequency of the current source may be stepped up to the point that, due to the persistence of vision, the lamp appears to be continually luminous.

In the embodiment of my invention illustrated in Fig. 3 the gaseous electric discharge lamp device has two anodes 25 and 25 and a thermionic cathode 24 sealed therein. Each of said anodes 25 is connected in series with the thermionic cathode 5 of a regulatory discharge device which is similar in all respects to that shown in Fig. 1. The anodes 6 of said regulatory devices are connected to the terminals of the secondary 26 of the transformer 27. The primary 28 of said transformer 27 is connected to the terminals of an alternating current source. The thermionic cathode 24 of the lamp device is connected by lead 29 to the mid-point of the secondary 26. Said transformer 27 has another secondary 30 and the circuit comprising lead 31, primary 34 of the transformer 34, 35, inductance 33 and variable resistance 32 is connected to said secondary 30. Said inductance 33 and said resistance 32 are connected in parallel. The grids 7 and the cathodes 5 of the regulatory devices are connected to the one of the terminals 105 of the secondaries 35 of the transformer 34, 35, resistances 36 being connected into the leads to said grids 7.

The apparatus shown in Fig. 3 is started into operation in the same manner as that shown in Fig. 1, that is, the cathodes 5, 5 and 24 are pre-heated before the operating potential is applied to the apparatus. The regulatory devices control the flow of current through the lamp device in the same manner as that shown and described in Fig. 1. In this case, however, current flows through the lamp device during a part of each phase of the alternating current due to the two anode structure of said lamp device and the lamp device appears continually luminous, more so than the lamp device of Fig. 1.

The embodiment of my invention illustrated in Fig. 4 is similar in many respects to that shown in Fig. 3 but in this embodiment the secondary 26 is divided into two parts 37 and 38 and a regulatory device is connected to a terminal of each of said transformer secondary parts 37 and 38 and said regulatory devices are connected to a single current instead of the cathode 24. A condenser 39 has been substituted for the resistance 33 in the circuit of the regulatory device. The apparatus illustrated in Fig. 4 is started into operation in the same manner as the apparatus of Fig. 3 and its operating characteristics are the same. It will be understood, of course, that the gaseous electric discharge lamp device is operable on a polyphase alternating current source where an appropriate number of anodes is provided in said lamp device.

What I claim as new and desire to secure by Letters Patent of the United States is:—

1. In combination an electric discharge lamp device of the elongated luminous positive column type comprising an envelope, a gaseous atmosphere therein, and electrodes sealed therein, a current supply for said device which periodically falls to zero, and a current control means connected in series with said device comprising a container, a gaseous atmosphere therein, electrodes and a grid sealed therein, and control

1,951,163

means connected to said grid, said grid control means being adjustable to time the duration of current impulses in said current control means and said lamp device whereby the mean value of current flow through the lamp device is controlled.

2. The method of controlling the mean current value of current flow in a gaseous discharge lamp device of the elongated luminous positive col-

umn type supplied with a potential which periodically falls to zero which consists in impressing on a grid in a discharge device connected in series with said lamp device a potential opposite to that impressed on the electrodes of the series connected discharge devices at least during part of the rise and fall of potential on said electrodes.
